UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

COUNTING-RELAY OPERATION.

Application filed July 6, 1925. Serial No. 41,598.

This invention relates to telephone systems and more particularly to systems in which machine switching apparatus is employed for establishing connections.

5 In certain types of machine switching telephone systems, it is customary to provide controlling mechanisms common to a plurality of connecting circuits for controlling the selective movement of automatic switches in 10 the establishment of connections. These mechanisms comprise a plurality of registers which operate in response to the transmission of impulses from a calling transmitter or to the actuation of keys in an operator's 15 keyboard to take up positions corresponding to the designations of called lines. With the registers in their set positions a series of counting relays arranged for association with said registers are successively operated 20 in variable combinations to determine the amount of movement to be imparted to the selective switches which are undergoing control. The several registers corresponding to units, tens, hundreds, etc. places of the called 25 numbers are generally provided with ten controlling positions or settings, one for each of the ten numeral digits. Subsequently, the counting relays cooperating with these registers are arranged to be energized 30 in any one of ten different combinations according to the settings of the registers.

It is the object of this invention to provide in a system of the foregoing character, a 35 counting relay set by means of which each of the controlling registers requires only a comparatively few settings to accomplish the usual control of the selector switches and in which terminating counting relays may be interpolated at any point in a train of counting 40 relays in order that a less number of counting relays may be employed in the train than the largest digit to be recorded.

A feature of this invention relates to an 45 arrangement of counting relays employing a less number of pairs of relays than the largest digit to be recorded and a pair of terminating relays which may be interpolated at any point in the train of relays.

This and other features of the invention 50 will be apparent from the following description taken in connection with the accom-

panying drawings, of which Fig. 1 discloses diagrammatically in automatic telephone exchange system from one subscriber to another and a sender associated with a district 55 selector switch and connected to the counting relays. Fig. 2 discloses the counting relays 0-0' to 4-4' along with relays 202, 203 and 204 arranged to count 10 digits, terminating relays 200 and 201, and diagrammatically illustrates the register 250, the above 5 relay 205 and other apparatus of the sender.

Reference is made to Patent No. 1,395,977 60 to F. A. Stearn et al. for a complete description of an automatic connection from a subscriber such as 100 through a district selector switch 150, an incoming selector switch, such as 125, a final selector switch such as 130 to the wanted subscriber 102. Reference 65 is further made to Patent No. 1,413,501 to F. A. Stearn for the detail description of the operating and associated circuits of relay 205 which is shown as relay 214 of this 70 patent.

While the invention is disclosed as particularly adapted for the control of selective switches in an automatically operated telephone system, it will be apparent from the following description that the invention has 80 a wider utility and that by slight modification may be effective for use with other types of apparatus.

Detail description.

Let it be assumed that a telephone call has been initiated at subscriber's station 100 and that brushes 101 and 102 are associated with terminals 103 and 104 through the agency of a line switch. The selection of the 90 district switch 150 by the line switch actuates the district switch apparatus including relay 107. The manipulation of the dial by subscriber at station 100 transmits interruptions to relay 108 to set the register switches 180 of the sender. The district switch is controlled by the register switch settings to associate brushes 117 and 118 with terminals 119 and 120 and the district selector sequence switch is rotated to a position where 95 conductors 113 and 114 are operatively associated with the apparatus of the incoming 100

selector switch 125 through sequence switch cams 111 and 112. Upon the selection of the incoming selector switch 125 its apparatus is actuated and the fundamental circuit is established which actuates the driving mechanism of the selecting brushes of the incoming switch.

Let it be assumed that at this time the dial interruptions have been transmitted from the 10 subscriber's station 100 to the register switches 180 of the sender in a manner described for the setting of the registers disclosed in Fig. 8 or 9 of Patent 1,395,977 and that the register relays such as shown in 15 Fig. 10 of this patent have been operated in accordance with a translation through the impulser and translator shown in Fig. 11 of this patent. Register 250 shown in Fig. 2 of this disclosure illustrates diagrammatically 20 the register relays such as shown in Fig. 10 of Patent 1,395,977, with the exception of relay 205 which is shown associated with the counting relays of Patent 1,413,501 to F. A. Stearn.

25 Contacts 206 to 210 may be any type of register contact associated with relays or a switch. Assuming that the contact 208 is established and that above 5 relay 205 is in an operated position, the terminating relays 30 200 and 201 are interpolated in the train of counting relays upon the second operation of the No. 1 counting relay and responsive to the seventh operation and release of stepping relay 242.

35 Upon the establishment of the fundamental circuit in the incoming selector switch 125, battery is associated with conductor 113 through a selector switch relay that controls the selective movement of the 40 switch and ground is associated with conductor 114 which establishes a circuit through the contact of sequence switch cam 225, windings of relays 241 and 242 and upper contact of counting relay 200. The operation 45 of the selector switch such as 125 is found in the above mentioned Patent 1,395,977 to cause the intermittent operation and release of stepping relay 242 as the brushes of the selector switch commutator move upwardly 50 over the segments of said commutator.

Relay 242 receives its initial energization upon the establishment of the fundamental circuit. A ground is thus associated through its contact, upper contacts of counting relays 3', 2', 1' and 0', winding of the 0 counting relay to battery, to cause the operation of the 0 counting relay. The operation of the 0 relay establishes a locking circuit for itself and an operating circuit for the 0' counting relay which is effected upon the release of relay 242 which maintains a shunt around the winding of the 0' counting relay during its operation. The operating circuit for 0' counting relay may be traced from 60 ground through the contact of sequence 65

switch cam 220, lower contact of the No. 1' counting relay, upper contact of the 0 counting relay, winding of 0' counting relay, winding of 0 counting relay to battery.

The operation of the 0' counting relay establishes an energizing circuit for relay 202 from battery, through its winding, normal contact of relay 203, lower contact of the 0' counting relay to ground through the contact of sequence switch cam 220. The operation of relay 202 establishes a locking circuit for itself and an operating circuit for relay 203 which is effective upon the release of the 0' counting relay. Until such time as the 0' counting relay is released, an obvious shunt ground circuit is maintained around the winding of relay 203.

The second operation of relay 242 establishes a circuit to operate the No. 1 counting relay from battery through its winding, upper alternate contact of the 0' counting relay, upper normal contacts of counting relays 1', 2' and 3' to ground through the contact of relay 242. The operation of the No. 1 counting relay establishes a locking circuit for itself and an operating circuit for 85

counting relay 1' which is effective upon the subsequent release of relay 242. This circuit is similar to the circuit traced for the 0' counting relay excepting that it is carried through the lower contact of the 2' counting relay. Upon the operation of the 1' counting relay, ground is removed from the locking circuit for the 0 and 0' counting 90

relays to cause their release. The release of the 0' counting relay removes the shunt around the winding of relay 203 causing its 100 operation in series with relay 202. A subsequent operation of relay 242 establishes a circuit to operate the No. 2 counting relay 105

which circuit may be traced from ground through contact of relay 242, upper normal contact of counting relays 3' and 2', upper alternate contact of the 1' counting relay, winding of the No. 2 counting relay to battery. The operation of the No. 2 counting relay establishes a locking circuit for itself and an operating circuit for the 2' counting 110

relay which is effective upon a subsequent release of stepping relay 242. The operation of the 2' counting relay removes ground from the locking circuit for the No. 1 and No. 1' counting relays to cause their release. The No. 3 and No. 3' counting relays are operated in the same manner as described for 115 the Nos. 2 and 2' counting relays. Upon a subsequent operation of stepping relay 242 a circuit is established to energize the winding of the No. 4 counting relay. This circuit may be traced from ground through the contact of relay 242, upper normal contact of the 4' counting relay, lower inside contact of the 3' counting relay, upper outside contact of relay 204, winding of the No. 4 counting relay to battery. The operation 120

125

130

of the No. 4 counting relay establishes a locking circuit for itself and an operating circuit for the 4' counting relay which is effective upon the release of stepping relay 242. 5 The operation of the No. 4' counting relay releases the Nos. 3 and 3' counting relay in the same manner as described for preceding counting relays. It will be noted that the locking circuit for the No. 4 and No. 4' 10 counting relay is not established through the contact of any other counting relay and therefore they remain locked until the sequence switch changes its position.

Since the second operation of the No. 1 15 counting relay has been assumed for cooperation with the setting of the register spring 208 a circuit may be traced for the second operation of the No. 0 and No. 0' counting relays which now take the place of 20 a No. 5 and No. 5' counting relay. The circuit for the reoperation of the 0 counting relay is established upon an operation of stepping relay 242 subsequent to the operation for the No. 4 counting relay and may be 25 traced from ground through the contact of relay 242, upper alternate contact of the No. 4' counting relay, upper normal contacts of the 3', 2', 1' and 0' counting relays, winding of the No. 0 counting relay to battery. The 30 operation of the No. 0 counting relay establishes an operating circuit for the 0' counting relay which is effective upon the release of stepping relay 242 in the same manner as previously described.

35 The reoperation of the 0' counting relay establishes an operating circuit for relay 204 which may be traced from battery through its winding, alternate contact of relay 203, lower contact of the 0' counting relay to 40 ground through the contact of sequence switch cam 220. The operation of relay 204 establishes a locking circuit for itself and further establishes a circuit for the operation of the terminating relay 201 when the digit 45 to be recorded is nine. The operation of relay 204 further establishes through its lowermost contact a path to ground for the reoperating circuit of counting relay 3'.

Upon the operation of the 0' counting 50 relay a circuit is established for the reoperation of the No. 1 counting relay. The energizing circuit for the No. 1 counting relay is established from ground through the contacts of stepping relay 242, upper alternate 55 contact of the 4' counting relay, upper normal contacts of the 3', 2' and 1' counting relays, upper alternate contact of the 0' counting relay, winding of the No. 1 counting relay to battery. Since contact 208 is closed 60 a circuit is also established from the operated ground for the No. 1 counting relay through the apparatus of the sender and register 250, contact 208, contact of sequence switch cam 221, 222 or 223 in accordance 65 with the selection made, lower inside con-

tact of the 4' counting relay, winding of terminating relay 201 to battery. The operation of the No. 1 counting relay establishes a locking circuit for itself and an operating circuit for the No. 1' counting relay. 70 The operation of terminating relay 201 establishes a locking circuit for itself and an operating circuit for the prime terminating relay 200. The operating circuits for the No. 1' relay and relay 200 are effective upon 75 the release of relay 242. The operation of the No. 1' counting relay is not effected at this time.

The operation of terminating relay 200 80 opens the fundamental circuit at its upper contact to arrest the upward movement of the selector switch elevator. The operation of relay 200 further establishes a circuit to energize the sequence switch magnet 240 from ground, through its lower alternate 85 contact, right lower contact of sequence switch cam 226, winding of magnet 240 to battery. The sequence switch is thus rotated from an even numbered position in which it is resting to an odd numbered position 90 where its movement is arrested awaiting the release of the terminating relay 200. The rotation of the sequence switch opens the locking ground for the counting relays including the terminating relays at the contact 95 of sequence switch cam 220. The release of terminating relay 200 establishes a circuit to again energize the sequence switch magnet 240 from ground through its lower contact, left contact of cam 226, winding of magnet 100 105 240 to battery. The sequence switch now rotates to an even numbered position where the fundamental circuit is again established through the contact of sequence switch cam 225, upper contact of relay 200 and other 110 apparatus of the sender.

The register 250 has a plurality of register combinations for incoming selector brush and group selection, final brush, tens and units selections. For each of the above 110 selections the sequence switch 260 is in an even numbered position and the conductors 230 to 234 are associated with the proper register contacts for the directive control of a selector switch. Assuming that the selection hereinbefore described was made for incoming group selection with the sequence switch in position 4 and that the sequence switch rotated from positions 4 to 6 upon the completion of this selection, the final 115 selector is now directly controlled for brush selection. Conductor 232 associated with the right contact of cam 222 is connected to register contacts the same as 206 to 210, one of which has been closed for this selection. 120

The final brush selection is ordinarily controlled with less than five digits and therefore the relay 205 is not operated so that the terminating relays may be interpolated 125 at some point in the train of counting re- 130

lays upon their first operation. It will be noted that with relay 205 in its normal position the operating path for relay 201 is from battery through its winding, left contact of relay 205, one of the contacts associated with sequence switch cams 221, 222 or 223, through a register contact such as one of contacts 206 to 210, upper contacts of the prime counting relays to ground through the contact of stepping relay 242.

Let it be assumed that the digit number to be recorded is nine. To record this digit the relay 205 is operated. It will be remembered that upon the first progressive operation of the counting relays, the 4 and 4' relays remain locked. Therefore, upon the next progressive operation of the counting relays a circuit path is established for the interpolation of the terminating relays for digit No. 9 through the register contact 206. This circuit may be traced from battery, through the winding of relay 201, lower inside contact of the 4' counting relay, a contact of sequence switch cam 221, 222 or 223, register contact 206 or a similar contact of other register units, upper inside contact of relay 204, upper alternate contact of the 3' counting relay to ground through the contact of stepping relay 242.

It is apparent from the above description that digits from 0 to 9 may be recorded on the relays disclosed and that the terminating relays may be interpolated at any point in the first or second progressive operation of such counting relays.

What is claimed is:

1. In a telephone system, a train of relays, means to successively operate said relays, another relay, and means to interpolate said other relay at any point in said train, said first means causing the operation of said second relay to terminate the operation of the relays of said train at the point of said interpolation.
2. In a telephone system, a train of counting relays, means to successively operate said relays, a single set of counting relays, and means to interpolate said single set at any point in the train, said first means causing the operation of said single set of relays as the terminating counting relays of said train.
3. In a telephone system, a train of counting relays for recording digits comprising a less number of pairs of relays than the largest digit to be recorded, means to operate said relays, a separate set of counting

relays, and means to interpolate said separate set at any point in said train.

4. In a telephone system, a train of counting relays for recording digits comprising a less number of pairs of relays than the largest digit to be recorded, means to operate said relays, a separate set of counting relays, and means to interpolate said separate set at any point of said train, said first means causing the operation of said separate set of relays as the terminating counting relays of said train.

5. In a system for controlling selective switches, a train of relays, means to progressively operate said relays in response to the movement of a switch, a terminating relay for controlling the extent of movement of a switch, and means to interpolate said terminating relay at any point in said train, said first means causing the operation of said terminating relay at the point of interpolation.

6. In a system for controlling selective switches, a train of counting relays of a less number of pairs than the largest digit to be recorded by the movement of a switch, means to progressively operate and reoperate said relays in response to the movement of a switch, a terminating relay for controlling the extent of movement of a switch, and means to interpolate said terminating relay at any point in said train during the operation or reoperation of said train, said first means causing the operation of said terminating relay at the point of interpolation.

7. In a telephone system, a train of relays, means to successively operate said relays, a terminating relay, a variable operable register arranged to be set for controlling the operation of said terminating relay, and means to interpolate said terminating relay at a point in said train of relays in accordance with the setting of said register.

8. In a system for controlling selective switches, a train of relays, means to progressively operate said relays in response to the movement of a switch, a terminating relay for controlling the extent of movement of a switch, a variably operable register arranged to be set for directive control of selective switches, and means to interpolate said terminating relay at a point of said train determined by the setting of said register.

In witness whereof, I hereunto subscribe my name this 30 day of June, A. D. 1925.

FRANKLIN A. STEARN.
